UNITED STATES PATENT OFFICE.

CHARLES HARRISON, OF VANCOUVER, BRITISH COLUMBIA, CANADA.

WOOD-REFUSE DESTROYER.

Application filed November 14, 1923. Serial No. 674,775.

To all whom it may concern:

Be it known that I, CHARLES HARRISON, citizen of the Dominion of Canada, residing at Vancouver, in the Province of British Columbia, Canada, have invented a certain new and useful Improvement in Wood-Refuse Destroyers, of which the following is a specification.

This invention relates to a refuse burner 10 for saw mill waste, and the improvements are directed to the combustion of this waste within a closed chamber, under such conditions as will prevent the delivery of black smoke and partially consumed particles to 15 the atmosphere.

The means by which these results are attained is fully described in the following specification, reference being made to the drawings by which it is accompanied, in 20 which:

Fig. 1 is a vertical longitudinal section through the burner and its connected parts.

Fig. 2 is a sectional plan of the same on the line 2—2 in Fig. 1.

Fig. 3 is a face view of the shaking refuse delivery chute to the burner.

Fig. 4 is a cross section of that part of the flue or passage from the burner to the smoke-stack in which is the spark quenching spray, being on the line 3—3 in Fig. 1.

In these drawings 2 represents a cylindrical burner chamber on a suitable foundation. The bottom of this chamber 2 is above the foundation and has a central square surface 4 from the four sides of which the floor slopes upward to the circle of the chamber wall at an angle of approximately thirty degrees. In the lower part of three of these slopes are the grates 5 through which the 35 air for combustion is delivered to the burner from arched apertures 6 in the outer wall of the burner and from the upper edge of the fourth side 7 a circular aperture delivers the products of combustion from this chamber 2 into a cylindrical combustion chamber 9.

The chamber 2 is of sheet metal, hooped with angle iron and lined with fire-brick and is roofed by crossed I-beams, the under- 50 sides of the lower series of which are encased in fire-brick with sheet metal channels between the webs of the lower series

of beams and extending over the side walls all around to shed the water therefrom.

The wood refuse to be consumed is delivered into the upper part of the burner 2 through a chute 10 which is hinge-connected at 11 to the frame of the conveyor by which the wood is elevated to the burner and the free end of this chute is supported 60 by chains 12 from an extension of the conveyor frame with a spring 13 at the connection of each chain.

The bottom of this chute 10 is formed of lengthwise spaced apart bars as a grizzly, 65 and beneath the chute 10 is a fixed chute 14 designed to catch the sawdust and the like which falls through the grizzly bars of the chute 10.

With this construction, as the refuse is 70 delivered from the conveyor into the chute 10, that chute swings on its pivots against the resistance of the springs, which shaking movement facilitates the passage of the sawdust through the bars. The lighter material thus falls separately into the burner 75 and is dried and burnt by the flame as it falls, while the heavier material is projected into approximately the centre of the burner.

The cylindrical combustion chamber 9 is, 80 like the chamber 2, constructed of sheet metal hooped at intervals and lined with fire-brick. At its connection of the burner proper its shell is secured to the shell of the 85 burner 2, and its other end is supported on rollers 15 that will permit of endwise expansion and contraction without distortion or undue strain.

In the outer end of this combustion chamber 9 is gland-packed at 16 one end of a metal water-jacketed spray passage 17, the other end of which is inserted and secured in the base of the smoke-stack 21. A water service from any suitable source of supply 90 is delivered at 18 to the lower part of this water jacket and the hot water is delivered at 19 from the upper part of the same for feed service to a boiler, or for other purpose where hot water may be required. A 95 separate water service is delivered through the jacketed wall of 17 to sprays 20 which spray across the entire cross section of the passage to quench any live sparks and wash

the free carbon from the products of combustion and prevent the delivery of black smoke to the atmosphere through the stack 21.

5 Residual water from the sprays 20 is drained from the jacketed passage 17 through an aperture 22 in the bottom at its middle or larger diameter.

10 The combustion chamber 9 may be air-jacketed to conserve the heat conducted through its fire-brick lining and utilize it for preheating the air for combustion. The drawings show it as provided with an air jacket 23, indrawing a supply at the outer 15 end and delivering through a duct 24 to apertures 25 in the wall of the burner 2 approximate the combustion zone of the refuse in it.

20 Concrete is generally used throughout the construction of this burner, except where exposed to heat that will be liable to injure it. Further, the furnace and combustion chambers are cylindrical and are sheathed with metal, which sheathing is 25 reinforced with iron hoops where exposed to greatest stress. The expansion and contraction of all parts exposed to heat are properly provided for.

30 The grate bars being disposed at an angle will keep free of ash accumulation, and being exposed directly to the incoming air currents derive the advantage of that current. The water-jacketed washing passage is so designed that the washing may be effected without injury to the structure.

35 Having now particularly described my invention, I hereby declare that what I claim as new and desire to be protected in by Letters Patent, is:

40 1. A refuse burner comprising in combination a cylindrical chamber having a closed top and grates in the bottom, means for delivering air for combustion to the grates, means for delivering the material to be burned into the upper part of the chamber, a cylindrical duct delivering the products of combustion from the lower part of the chamber to the smoke stack, said duct having a length the bottom of which drains 45 to an outlet intermediate its ends, and means for delivering a spray of water across the area of said length of the duct.

50 2. A refuse burner, comprising in combination, a cylindrical chamber having a closed top and grates in the bottom, means for delivering air for combustion to the grates, means for delivering the material to be burnt into the upper part of the chamber, a cylindrical duct delivering the products of combustion from the lower part of the chamber to the smoke-stack, said duct having a length which is of metal and water-jacketed, the bottom of which water-jacketed length drains to an outlet inter-

mediate the ends, and means for delivering 65 a spray of water across the area of this metal portion of the duct.

3. A refuse burner, comprising in combination, a cylindrical chamber having a closed top and a bottom sloping upward 70 from each side of a square central area, grates in three of the four sloping sides of the bottom, means for delivering air for combustion directly to these grates, means for delivering the material to be burnt into the upper part of the chamber, means for delivering the products of combustion from the lower part of the chamber on the side which has no bottom grate, a horizontally 75 disposed cylindrical combustion chamber through which the products of combustion 80 from the burner chamber pass to the smoke-stack, said combustion chamber secured to the burner chamber and having provision 85 permitting endwise expansion therefrom, and means for delivering a spray of water across the cross section area of the combustion chamber adjacent its delivery to the smoke-stack.

4. A refuse burner, comprising in combination, a cylindrical chamber having a closed top and a bottom sloping upward from the four sides of a square central area, grates in the sloping sides, means for delivering air for combustion directly to these grates, means for delivering the material to be burnt into the upper end of the cylindrical chamber, means for separating the smaller from the larger material during 90 such delivery, means adjacent the lower part of the chamber for delivering the furnace gases therefrom, a horizontally disposed cylindrical combustion chamber into which the furnace gases are delivered, said combustion chamber secured to the burner chamber, means for supporting the other end of the combustion chamber and providing for endwise expansion from the burner chamber, a water-jacketed passage 95 connecting the outer end of the combustion chamber to the smoke-stack, and means in this jacket for delivering a spray of water 100 across its area.

5. A refuse burner, comprising in combination, a cylindrical chamber having a closed top and a grate in the bottom, means for delivering air for combustion to the grates, means for delivering the products of combustion from the lower part of the chamber to the smoke-stack, means for delivering the material to be burnt into the upper part of the chamber, means during 115 delivering for separating the small material from the larger and for projecting the larger toward the smoke-stack delivery, and the smaller adjacent the opposite side of the burner.

6. A refuse burner, comprising in com-

bination, a cylindrical chamber having a closed top and grates in the bottom, means for delivering air for combustion to the grates, means for delivering the material to be burnt into the upper part of the chamber, a horizontally disposed cylindrical duct delivering the products of combustion from the lower part of the chamber to the smoke- stack, a casing around this duct maintaining an air space through which space air ¹⁰ is conducted and preheated for delivery to the furnace chamber.

In testimony whereof I affix my signature.

CHARLES HARRISON.
